COMBINED WHEEL AND TIRE

Harold D. Hulterstrum, Baraboo, Wis., assignor to Flambeau Plastics Corporation, a corporation of Wisconsin

Filed Oct. 31, 1960, Ser. No. 62,687

Term of patent 14 years

(Cl. D14—30)

FIGURE 1 is a perspective view of a combined wheel and tire showing my novel design;

FIGURE 2 is a front elevational view thereof;

FIGURE 3 is a rear elevational view of the wheel shown in FIGURE 1; and

FIGURE 4 is a side view of the wheel shown in FIGURE 1.

I claim:

The ornamental design for a combined wheel and tire, substantially as shown.
